UNITED STATES PATENT OFFICE.

THOMAS K. TRAVERS, OF SAN DIEGO, CALIFORNIA.

BOXING-GLOVE.

1,150,648.

Specification of Letters Patent.

Patented Aug. 17, 1915.

Application filed March 18, 1914. Serial No. 825,641.

To all whom it may concern:

Be it known that I, THOMAS K. TRAVERS, a citizen of the United States, and a resident of San Diego, in the county of San Diego and State of California, have invented a new and useful Improvement in Boxing-Gloves, of which the following is a specification.

My invention is an improvement in boxing gloves, and has for its object to provide a glove of the character specified, wherein a glove is provided having a resilient socket at one end for receiving the hand of the user, and having a packing at the 10 end of the glove remote from the socket and having a space between the packing and the adjacent end of the socket, the arrangement being such that when a blow is dealt the soft portion of the glove first strikes the 15 object and the socket extends absorbing the impact of the hand, thus breaking the force of the blow.

In the drawings: Figure 1 is a front view of the improved glove, and Fig. 2 is a longitudinal section.

The present embodiment of the invention comprises a glove of approximately pear-shape and composed of an outer covering 1 of approximately circular cross section and 20 having one end open. A resilient or elastic socket 3 is arranged within the outer covering, one end of the socket being open and the said open end is secured to the open end of the outer covering by means of a stitching 25 ing 4, or the like.

The socket is shaped to fit the hand of the user, and in the present instance is in the form of a mitten, being merely an open ended socket adapted to receive the doubled fist 30 of the user.

A lining is arranged within the outer covering 1, the said lining consisting of a substantially cylindrical body 9 and a cap or cover 16 secured to the inner end of the 45 body, and the said lining is of semi-rigid material, as for instance, wickerwork. This lining is open at its outer end and extends from the open end of the socket a little more than half the length of the glove. The 50 socket 3 is arranged within this lining, and the lining is of such length with respect to the socket that when a blow is struck and the socket stretches, the hand of the user will not contact with the cap or cover 16 55 or with the glove proper, to injure the hand.

The space between the lining and the in-

terior of the outer covering 1 is filled with packings 6, 8 and 10, the packing 6 being at the outer end of the glove, the packing 8 at the inner end, and the packing 10 between the packings 6 and 8. The packings 6 and 8 are of suitable material, as for instance, curled hair, and the packing 10 is in the present instance of felt or like soft fibrous material. It is obvious, however, that the 60 said space may be filled with a homogeneous packing of any desired character. The packing 8 is in such position that when the glove is in place the said packing will encircle the wrist of the user. The filling 10 65 is just of sufficient depth to cover and conceal the framework or lining 9, and said lining or framework provides a stiffening for the body of the glove to keep the glove in shape, and this stiffening and reinforcing action is assisted by the particular type of packing 10 used. The only object in 70 making the packing 10 of the character mentioned is to assist in this stiffening or reinforcing function. The wrist portion of 75 the glove is approximately cylindrical, but beyond this portion the glove is enlarged, and the end remote from the socket is round- 80 ed, as shown.

The outer covering 1 may be continuous 85 to the open end of the socket or a wrist piece 12 may be arranged between the open end of the covering and the socket as shown in the present instance. This wrist piece is connected at one end to the open end of 90 the outer cover 2 as shown at 13, and at the other end the said wrist piece is connected to a double reinforcement 14, which partially encircles the socket, overlying that end of the framework 9 adjacent to the open end 95 of the glove. The framework or lining 9 is provided at the open end of the glove with an annular rib or enlargement 15, and it will be noticed that the said framework is approximately frusto-conical, and that it increases in cross section gradually from the 100 open end of the glove toward the packing 6.

The wrist piece and the socket are slit at the open end of the glove, as shown at 17, and eyelets 18 are provided at each side of 105 the slit for receiving a lace 19 to permit the glove to be held on the hand. The lining or framework 9 may be of any suitable material that will hold the glove in proper shape while being sufficiently resilient to 110 prevent injury to the person struck. The outer cover 1 is also provided with a lining

20 of leather or the like to strengthen the same and to assist in holding the cover in shape. The slit 17 extends near to the outer covering 1 at the wrist. The socket is preferably provided with openings 21 for ventilation, and the open end of the socket must be securely attached to the glove.

10 In use the hand of the user is inserted in the socket, and it will be evident that when a blow is struck, the socket will stretch to cushion the jar of the blow. The openings 21 in addition to their function of providing ventilation, also tend to equalize the pressure in the space between the lining 9 and 15 the socket.

I claim:—

1. A boxing glove consisting of a padded body portion having a fist opening, a lining for the said opening, a socket secured to the mouth of the said opening and of elastic material, and extending into the said lining but 20

normally short of the inner end thereof to permit the socket to stretch when a blow is struck.

2. A boxing glove consisting of a padded body portion provided with a fist opening, a socket arranged within the body portion and secured to the mouth of the fist opening, said socket being of elastic material and a lining encircling the socket and extending beyond the socket into the body portion to provide an empty space between the inner end of the lining and the inner end of the socket to permit the socket to stretch when a blow is struck, said lining being of flexible material and semi-rigid and of approximately cylindrical form.

THOMAS K. TRAVERS.
